UNITED STATES PATENT OFFICE.

ROSE O'NEILL WILSON, OF DAY, MISSOURI.

DESIGN FOR A DOLL.

44,393.

Specification for Design.

Patented July 22, 1913.

Application filed May 21, 1913. Serial No. 769,091. Term of patent 14 years.

To all whom it may concern:

Be it known that I, ROSE O'NEILL WILSON, a citizen of the United States, residing at Day P. O., in the county of Taney and State of Missouri, have invented a new, original, and ornamental Design for a Doll, of which the following is a specification, reference being had to the accompanying drawing, forming a part thereof.

The figure is a perspective view of a doll, showing my new design.

I claim—

The ornamental design for a doll as shown.

ROSE O'NEILL WILSON.

Witnesses:

A. A. KIETHLEY,
I. G. O'NEILL.
